UNITED STATES PATENT OFFICE.

GEORGE C. PEARSON, OF TROY, PENNSYLVANIA.

DESIGN FOR A GARDEN-TOOL.

SPECIFICATION forming part of Design No. 29,443, dated October 4, 1898.

Application filed August 18, 1898. Serial No. 688,934. Term of patent 7 years.

To all whom it may concern:

Be it known that I, GEORGE C. PEARSON, a citizen of the United States, residing at Troy, in the county of Bradford and State of Pennsylvania, have invented and produced a new and useful Design for a Garden-Tool, of which the following is a specification.

The essential feature of my design consists in the peculiar shape of the blade, as clearly illustrated in the accompanying drawings, forming a part of this specification, in which—

Figure 1 is a face view of a garden-tool constructed in accordance with my invention. Fig. 2 is a sectional view on the line 2 2 of Fig. 1.

Referring to the drawings in detail, A rep-

resents a blade having a sharp edge B at its end. A reentrant notch C is made in one side of the blade, the edges of said notch being beveled and sharpened, as represented at D. 20

E represents a ferrule or sleeve connected with the blade, and said blade is bent or deflected to one side, as shown at F.

Having thus described my invention, what I claim as new, and desire to secure by Letters 25 Patent of the United States, is—

The design for a garden-tool, substantially as herein shown and described.

GEORGE C. PEARSON.
